UMBRELLA

Walter L. Weakland, Platte City, Mo., assignor to
Rockledge Manufacturing Company, a corporation of Missouri

Application December 30, 1948, Serial No. 68,109

4 Claims. (Cl. 135—46)

1

The present invention relates in general to umbrellas and it deals more particularly with the construction and arrangement of articulated parallelogram linkages for off-setting the umbrella canopy or cover from the main post or pedestal.

The primary object of the invention is to provide an umbrella wherein the canopy or sheltering cover can be centered on the main post or may be off-set varying distances from the main post.

To this end it is an object of the invention to provide in the umbrella shaft an articulated parallelogram linkage of improved form, which linkage is simple and compact in construction, sturdy and efficient in operation and relatively inexpensive to manufacture.

Another object is to provide a positive stop means limiting the extent of movement of the parallel links carried by the main post of the umbrella; a further object is to provide a simple but efficient arrangement for locking said parallel links in different off-set positions relative to the main post.

Other and further objects together with the features of novelty whereby the objects are achieved will appear in the course of the following description of the invention.

In the accompanying drawings which form a part of the specification and are to be read in conjunction therewith, and in which like reference numerals are employed to indicate like parts of the various views,

Fig. 1 is a side elevational view showing the umbrella in raised position, the fabric covering of the canopy having been omitted for the sake of clarity; the vertical or central position of the umbrella head is shown in solid lines and the off-set position is shown in dotted lines,

Fig. 2 is a side elevational view showing the umbrella in lowered position and turned about its vertical axis 90° from its Fig. 1 position;

Fig. 3 is an enlarged cross sectional view taken along the line 3—3 of Fig. 1 in the direction of the arrows;

Fig. 4 is an enlarged cross sectional view taken along the line 4—4 of Fig. 1 in the direction of the arrows;

Fig. 5 is an enlarged cross sectional view taken along the line 5—5 of Fig. 1 in the direction of the arrows;

Fig. 6 is an enlarged cross sectional view taken along the line 6—6 of Fig. 2 in the direction of the arrows, and

Fig. 7 is a fragmentary cross section taken

2

through the parallel arms showing a modified form of connection therebetween.

Referring more particularly to the drawings, the umbrella has a stem or post divided into 5 three sections. The elongated lower section 10 and the short upper section 12 are tubular, while the intermediate section is composed of a pair of parallel bars or links 14 and 16. It will be noted that the bars are pivoted to yokes 18 and 19 by means of bolts or pins 20, the upper yoke being formed by flattening the end of tube 10 and the lower yoke being a separate channel-shaped member welded or otherwise rigidly affixed to the upper end of tube 10.

10 The two upper pivot pins and the two lower pins define the four corners of an articulated parallelogram; thus, as shown by dotted lines in Fig. 1, when the bars or links are pivoted to an inclined position, they maintain tube 12 parallel to post 10 so that it remains upright but off-set 15 from the main post.

20 In their vertical position bars 14 and 16 are spaced very closely together and preferably about one another. As they pivot downwardly to the right (see Fig. 1) it will be clear that the space 25 between the bars tends to gradually increase until they reach a position perpendicular to the line X—X passing through the pivots 20. At that position, the distance between them is at a maximum and further downward movement gradually brings the bars close together again.

25 According to the invention the angle Y is greater than 45°, which causes the space between the two bars or links to maximize before they have been moved downwardly 45°. Preferably angle Y is about 55° causing the distance between the bars to maximize at an inclination of about 35° from the vertical; downward movement of an additional 35° (i. e., to a position 70° down from the vertical) brings the bars very 30 close together again just as they were in their original upright position. At this point, they begin to bind against one another, making it impossible for them to descend enough further to 35 reach and pass through horizontal position; this maintains the open umbrella canopy at all times above the top of post 10, eliminating the possibility of the fabric being torn or the umbrella otherwise being injured by the top of the post 40 as might accidentally occur if the bars or links could drop below horizontal position.

45 From the foregoing, it will be clear that the bars 14 and 16 can swing in an arc between a vertical position and a predetermined inclined 50 position, the latter preferably being at 70° from

the vertical and at all events lying in the region between 45° and 90° from the vertical. Between the two limits of their arc, the bars may be locked in various positions by the arrangement about to be described.

The locking arrangement comprises a pair of plates 24 and 26, the former being welded to bar 14 but extending over bar 16 and the latter being welded to bar 16 but extending over bar 14. The plates are located at approximately the mid-point of the two bars and it will be evident that these points on the respective bars shift axially of one another as the bars swing up or down about their pivots. Each bar has a series of notches 28 under the plate which extends over it from the other bar, the respective plates having tongues 30 adapted to seat in the notches. In order to clamp the two plates together and thus prevent the bars from shifting axially relative one another, a bolt 31 is screwed into a tapped hole in plate 26, its shank extending through a passageway between the bars provided by the cut-out portions 32 and 34 and through an elongated slot 36 in plate 24.

Preparatory to changing the pitch or angle of the bars, bolt 31 is loosened, and after the change is made, it is retightened with the tongues 30 seated in a different set of notches 28; this once more makes it impossible for the bars to travel axially relative to one another and accordingly their adjusted angular position relative the post 10 cannot change.

Fig. 7 shows a modified arrangement for locking the bars 14 and 16 in adjusted position. This comprises a series of tapped holes 38 in one of the bars, located at approximately the mid-point of the bar. A thumb screw 40 carried by the other bar shifts from one hole 38 to the next as the bars shift axially during adjustment of angle of their inclination, and the thumb screw can be advanced into any one of the holes 38 to lock the bars in adjusted position.

The canopy or cover of the umbrella is more or less conventional and need not be described in detail. Briefly, its frame work comprises ribs 42 hinged connected to the upper end of the short post 12. Each rib has a support or stay 44 having one end hinged to the associated rib at 46 and the other end hinged to a sleeve 48 encircling the post. In the raised condition of the umbrella, the sleeve is supported by a spring latching member 50; this may be depressed to permit sleeve 48 to pass downwardly over the latching member thereby to lower the umbrella as shown in Fig. 2.

From the foregoing it will be seen that the invention is one well adapted to attain all of the ends and objects hereinbefore set forth as well as other advantages which are obvious and which are inherent to the apparatus.

It will be understood that certain features and subcombinations are of utility and may be employed without reference to other features and subcombinations. This is contemplated by and is within the scope of the claims.

Inasmuch as many possible embodiments of the invention may be made without departing from the scope thereof, it is to be understood that all matter herein set forth or shown in the

accompanying drawings is to be interpreted as illustrative and not in a limiting sense.

Having described my invention, I claim:

1. In an umbrella, an articulated parallelogram with posts forming two opposite sides thereof and links forming the remaining two sides, the links pivoted to each post at points disposed along a line diagonal of the axis of the post, a connecting device carried by one of the links, the other link having a series of sockets the different ones of which register with said connecting device in different positions of the links, and means for advancing said device into any one of said sockets thereby to prevent axial shifting of the links relative to one another.

2. An umbrella as in claim 1 wherein said device comprises a screw threaded member and said sockets are threaded to receive said member.

3. In an umbrella, an articulated parallelogram with posts forming two opposite sides thereof and elongated links forming the remaining two sides, the links pivoted to each post at points disposed along a line diagonal to the axis of the post, the longitudinal axes of said links being in the same vertical plane, a pair of plates on opposite sides of said plane, each disposed in lateral bridging relationship beside the respective links, means for drawing said plates together to clamp said links therebetween, thereby to prevent axial shifting of the links relative to one another, at least one of said plates being integral with one of said links, the other link having a series of axially spaced notches under said one plate, and a projection on said one plate adapted to seat in any one of said notches when said plates are drawn toward one another.

4. In an umbrella, an articulated parallelogram with posts forming two opposite sides thereof and elongate links forming the remaining two sides, the links pivoted to each post at points disposed along a line diagonal to the axis of the post, the longitudinal axes of said links being in the same vertical plane, a pair of plates on opposite sides of said plane each disposed in lateral bridging relationship beside the respective links, one of said plates being integral with one of said links and the other plate being integral with the other link, and means for drawing said plates together to clamp said links therebetween, thereby to prevent axial shifting of the links relative to one another.

WALTER L. WEAKLEND.
